BASE MEMBER FOR DUPLICATING DEVICE
Max J. Doppel, 1920 W. Sunnyside Ave., Chicago, Ill.
Filed Dec. 20, 1963, Ser. No. 332,116
3 Claims. (Cl. 101—269)

This invention relates to improvements in duplicating devices, and more particularly to an improvement in a small inexpensive duplicating device that is provided with a stencil and is capable of making a large number of copies with the stencil.

In my U.S. Patent No. 2,203,192 there was disclosed a duplicating device which was portable, inexpensive and could be used for making a large number of copies from a stencil.

The duplicating device after many years of use has been found inadequate in certain respects. One disadvantage thereof has to do with the base member incorporated in this prior device. The prior base member disclosed in my earlier application had a plate incorporated therein which was fixedly attached thereto and accordingly when the arcuate printing surface of my device's printing member was forced against the plate and rockably actuated, the printing stock located therein had no actuating force from the plate member which would cause it in turn to be forced against the arcuate printing surface. Also, the size of the printing stock to be used in my duplicating device was limited by the manner in which it was located on the printing plate of my device.

In order to obviate these difficulties I have provided an improved means of mounting a plate on the base member of my device which biases the plate upward thereby causing it to be forced against the arcuate printing surface of my printing member when the same is operably actuated with relation thereto and accordingly when a piece of printing stock is disposed on the plate, the same will be sandwiched between the arcuate surface of the printing member and the plate and these members perform a squeezing or sandwiching effect on the printing stock. Also by providing a key member in combination with spring biased spotting pegs the location of different sized stock on the printing plate can be accomplished without obstructing contact between a printing member and printing plate.

It is therefore an object of this invention to provide a new and improved duplicating device.

It is further an object of this invention to provide a new and improved means for mounting a plate to the base member of a duplicating device whereby the plate is positioned to bias the printing stock upward or against the arcuate surface of a printing member.

It is still further an object of this invention to provide a new and improved means for locating printing stock on a printing plate whereby varied sizes of printing stock can be utilized therein.

It is still further an object of this invention to provide a locating means which doesn't obstruct contact of the printing member's arcuate surface with the plate.

It is still further an object of this invention to provide a means for locating printing stock on a printing plate of a duplicating device wherein the height of the locating means can be varied.

Other and further objects of this invention will become more readily apparent from reading the specification with the drawing in which:

FIGURE 1 is a perspective view of my new and improved duplicating device,

FIGURE 2 is a top view of the base member of the duplicating device illustrated in FIGURE 1,

FIGURE 3 is a cross-sectional view of FIGURE 2

taken along a plane passing through the line 3—3 and looking in the direction of the arrows,

FIGURE 4 is a side elevation view of FIGURE 2 taken on a plane passing through the line 4—4 and looking in the direction of the arrows,

FIGURE 5 is a cross-sectional view illustrating the cooperation of my spotting pegs utilized for locating the printing stock taken on a plane passing through the line 5—5 and looking in the direction of the arrows,

FIGURE 6 is a cross-sectional view of a key member cooperating with one of my spotting pegs to vary the size of printing stock to be located, taken on a plane passing through the lines 6—6 and looking in the direction of the arrows, and

15 FIGURE 7 is a view of the key member mentioned in FIGURE 6.

Referring more specifically to the figures in the drawing, wherein like characters of reference indicate corresponding parts throughout the views, I have provided a 20 printing member 10 with substantially the same configuration of the platen illustrated in my prior aforementioned patent which consists of a hollow body or case with an arcuate printing surface (not shown) at the bottom thereof. The printing member has segmental gears 25 13 at each end thereof disposed in opposing relationship to each other. The base member 12 of my duplicating device includes a reciprocally mounted plate 17 positioned on the top surface thereof interposed between a pair of racks 15, as illustrated in FIGURE 2. The racks 15 are positioned to intermesh with the segmental gears 13 to enable the printing platen to be rockably actuated thereby providing an oscillatory motion of the arcuate printing surface thereof.

As seen from FIGURES 2 and 3 a plurality of rivets 35 20 have one end thereof fixedly attached to the plate 17 and the other ends thereof protruding through apertures 14A of the base support portion 14 to locate the plate 17 with respect to the base member. The rivets are disposed near the corners of the plate. The stems 20B of 40 the rivets are slidably positioned in the apertures 14A and their motion upward with respect to the base support portion 14 is limited by the heads 20A of the rivets.

As seen from FIGURES 2, 5 and 6 the locating means for the printing stock consists of spotting pegs 22 having pin shaped domes 22A with shoulder portions 22B disposed in the recesses 14B of the base support portion 14. Spring biasing members 22C are located in the recesses 14B to force the spotting pegs upward and the shoulder portions against the bottom surface of the plate 17. The spotting pegs 22 are disposed at one end of the plate to cause said end to be supported upward of the base support portion 14. The pin shaped domes 22A protrude through openings 17A in the plate and one of 45 these pin shaped domes is disposed on one side of the plate while three of them are disposed at the other side thereof as illustrated in FIGURE 2. The pin shaped domes are disposed with respect to each other in a manner that different sizes of printing stock can be positioned 50 therein by depressing one of the pin shaped domes of the spotting pegs with a U-shaped key 28 which includes a short arm 28A and a long arm 28B. As illustrated in FIGURE 6, the long arm is positioned over the top of a dome to depress it while the short arm 28A is disposed 55 beneath the plate 17. The key is spring tempered to enable it to be clamped to the plate as illustrated in FIGURE 6.

By providing the spring biased spotting pegs for locating the printing stock, the arcuate surface of the printing member depresses the pin shaped domes when contact is made therewith so that the spotting pegs do not impede

contact with the printing stock. The plate is being biased upward by the pin shaped domes forces printing stock located thereon into firm contact with the arcuate shaped printing surface of the printing member thereby producing better copy. The U-shaped key working in combination with the depressible pin shaped domes enables different size printing stock to be utilized as seen by the different sizes in FIGURE 2. Accordingly the objects of my invention are accomplished efficiently and inexpensively.

It should be realized that although I show a specific arrangement of the spotting pegs working in combination with one key, I intend this invention to cover a device that has other arrangements for the spotting pegs with the possible utilization of more than one key. Also, the specific construction that I have described in connection with a specific type of duplicating device should not be taken to limit my invention. I intend this invention to apply to a base that does not include racks.

Having now particularly described and ascertained the nature of my said invention and the manner in which it is to be performed, I declare that what I claim is:

1. A duplicating device having an improved base comprising: a base support portion, a reciprocally mounted plate disposed over said base support portion, a plurality of rivets having one end fixedly attached to said plate proximately disposed to each side of said plates, said rivets having the other ends thereof protruding through said base with the stems thereof slidably disposed with respect thereto, said rivets having heads at said other ends thereof limiting the sliding movement of said stems with respect to said base, a plurality of spring biased spotting pegs vertically slidably received in said base, said plate having apertures at one end thereof disposed to receive said pegs, said spotting pegs having shoulder portions biased against said plate to cause one end of said plate to be supported upward and apart from said base, said spotting pegs having pin shaped domes protruding through said apertures in said plate, said domes of said spotting pegs being disposed and depressible to align and receive different size printing stock for printing.

2. In a duplicating device, as defined in claim 1, at least one key removably attached to said plate, said key being disposable to depress one of said domes of said spotting pegs, said key having a U shape including a pair of arms with one arm of the U being shorter than the other arm, said long arm being disposable over the top of said domes to depress one of said domes while said short arm being disposed beneath said plate and being spring tempered to enable removable association of said key with said plate, whereby different sized cards can be received and positioned by said plate by selectively depressing said domes with said long arm of said key, and said plate is

forced upward to cause contact with a printing surface thereby moving printing stock located thereon into firm engagement with said printing surface.

3. An improved duplicating device that cooperates with 5 a printing member having an arcuate printing surface that has segmental gears at each side thereof, comprising: a base, a base support portion, a reciprocally mounted plate disposed on said base support portion, a rack disposed at each side of said base support portion, said 10 racks having teeth that intermesh with said segmental gears to provide a rotating motion of said arcuate surface of said printing member on said plate, a plurality of rivets having one end fixedly attached to said plate proximately disposed to each side of said plates, said rivets having the other ends thereof protruding through said base with the stems thereof slidably disposed with respect thereto, said rivets having heads at said other ends thereof limiting the sliding movement of said stems with respect to said base, a plurality of spring biased spotting pegs vertically 15 slidably received in said base, said plate having openings at one end thereof disposed to receive said pegs, said spotting pegs having shoulder portions biased against said plate to cause one end of said plate to be supported upward of said base, said spotting pegs having pin shaped domes protruding through said apertures in said plate, said domes of said spotting pegs being disposed and depressible to align and receive different sized printing stock for printing, a key removably attached to said plate, said key being disposable to depress one of said domes of said spotting pegs, said key having a U shape including a pair of arms with one arm of the U being shorter than the other arm, said long arm being disposable over the top of said domes to depress one of said domes while said short arm being disposed beneath said plate and being spring tempered to enable removable association of said key to said plate, whereby different sized cards can be received and positioned by said plate by selectively depressing said domes with said long arm of said key, and 20 said plate is forced into contact with said arcuate surface of said printing member when said printing member depresses said plate.
